UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DES CN FOR A LADY'S DOUBLE-BREASTED JACKET.

SPECIFICATION forming part of Design No. 14,459, dated November 27, 1883.

Application filed September 26, 1883. Term of patent 3½ years.

To all whom it may concern:

Be it known that I, MARY TURNER, of the city, county, and State of New York, have invented and produced a new and original Design for a Pattern of a Lady's Double-Breasted Jacket, (numbered 8,910;) and I do hereby declare that the engraved prints accompanying this specification convey to any one accustomed to using paper patterns a clear understanding of how a garment made up by the pattern will appear.

The design shows a closely-fitted back and closely-fitted fronts, the latter showing lapels at their tops. A side plait formed on the back 15 part of each side back below the waist over-

laps the adjoining back section, the upper corners of the two plaits meeting at the lower end of the center seam, which exhibits a double box-plait folded underneath. Coat-sleeves and a standing collar are added.

What I claim as my invention, and desire to secure by Letters Patent, is—

The design for a lady's double-breasted jacket, as shown in the engraved prints accompanying this specification.

MARY TURNER.

Witnesses:

ALFRED FRANCIS,
MARCELLUS CARLETON SHATTUCK.
